DESIGN FOR AN OIL BURNER CASING

Frederick W. Scheifele, Audubon, N. J.

Application April 27, 1935, Serial No. 56,598

Term of patent 14 years

To all whom it may concern:

Be it known that I, Frederick W. Scheifele, a citizen of the United States, residing at Audubon, in the county of Camden and State of New Jersey, have invented a new, original, and ornamental Design for an Oil Burner Casing, of which the following is a specification, reference being had to the accompanying drawing, forming part thereof.

Figure 1 is a side view, and
Fig. 2 is a rear end view, of an oil burner casing.

I claim:
The ornamental design for an oil burner casing, as shown.

FREDERICK W. SCHEIFELE.
